(57) **CLAIM**

The ornamental design for a screw of a camera mount, as shown and described.

DESCRIPTION

FIG. 1 is an upper perspective view of a first embodiment of a screw of a camera mount of our new design;

FIG. 2 is a front view thereof;

FIG. 3 is a rear view thereof;

FIG. 4 is left view thereof;

FIG. 5 is a right view thereof;

FIG. 6 is a top view thereof; and

FIG. 7 is a bottom view thereof.

FIG. 8 is an upper perspective view of a second embodiment of a screw of a camera mount of our new design;

FIG. 9 is a front view thereof;

FIG. 10 is a rear view thereof;

FIG. 11 is left view thereof;

FIG. 12 is a right view thereof;

FIG. 13 is a top view thereof; and

FIG. 14 is a bottom view thereof.

FIG. 15 is an upper perspective view of a third embodiment of a screw of a camera mount of our new design;

FIG. 16 is a front view thereof;

FIG. 17 is a rear view thereof;

FIG. 18 is left view thereof;

FIG. 19 is a right view thereof;

FIG. 20 is a top view thereof; and,

FIG. 21 is a bottom view thereof.

The broken lines in the figures represent unclaimed portions of the screw of a camera mount and form no part of the claimed design.

1 Claim, 18 Drawing Sheets
